CLAIM

The ornamental design for a combined saddle and tack rack, as shown and described.

DESCRIPTION

FIG. 1 is a front elevational view of a combined saddle and tack rack showing my new design;

FIG. 2 is a top plan view thereof;

FIG. 3 is a right side elevational view thereof, the left side being a mirror image of the side shown;

FIG. 4 is a rear elevational view thereof;

FIG. 5 is a front elevational view of a modified form of the combined saddle and tack rack shown in FIG. 1; and

FIG. 6 is a right side elevational view of FIG. 5, the left side being a mirror image of the side shown.

Fig. 4

Fig. 3
